BOILER

Howard J. Kerr, Westfield, N. J., and Ivar L. Langvand, Barberton, Ohio, assignors to The Babcock & Wilcox Company, Bayonne, N. J., a corporation of New Jersey

Application December 6, 1928, Serial No. 324,084
Renewed June 26, 1934

10 Claims. (Cl. 122—302)

The invention relates particularly to boilers of the so-called Stirling type, and will be described in reference thereto. The accompanying drawing indicates a vertical sectional view through a boiler showing an embodiment of the invention.

For the purposes of illustration, the invention is shown as embodied in a Stirling boiler having a lower water drum 1, and front, middle and rear upper steam and water drums 2, 3 and 4 respectively. Each of the upper drums is connected to the lower drum by a bank of tubes, a front bank 5, a middle bank 6, and a rear bank 7 serving to connect the front, middle and rear upper drums respectively to the lower drum. In front 10 of the front bank of tubes is a source of heat indicated as a grate 8 beneath an arch 9, although it is to be understood that any other suitable source of heat may be supplied.

The hot gases from the source of heat are directed upwardly over the front bank of tubes, downwardly over the middle bank, and upwardly over the rear bank to the flue 10. For this purpose, suitable baffling is provided and in the form shown, this baffling comprises a baffle 30 disposed on the front row of the middle bank.

Disposed adjacent the rear of the bank 6 is a baffle 31 which with the baffle 30 forms the second pass through which gases flow over the bank 6, this bank being included in that pass. The rear bank 7 connects the lower drum with the rear upper drum 4, and some of the tubes 7' are carried forward and are connected to the middle drum 3. These tubes 7' may be used to support a baffle 16.

By the above arrangement, there is provided a plurality of tubes connecting each of the front and middle upper drums to the lower water drum, and of the tubes connecting one of these upper drums to the lower drum, some are disposed in a relatively hot pass and others in a relatively cool pass. For example, of the tubes connecting the lower drum to the upper front drum, some are exposed to the hot gases in the combustion chamber, while others are disposed in the second pass where they are subjected to the same gases after they have been cooled by contact with the front bank of tubes.

The drums 3 and 4 are connected by steam circulators 17 and the drums 2 and 3 by steam circulators 18 and water circulators 19, although the latter may be omitted under certain conditions. The rear upper drum is provided with a steam outlet 20 and also with a feed water inlet 21.

The front and middle drums are connected

to the lower drum by banks of tubes which are substantially parallel to each other and spaced apart a greater portion of their lengths. In the parallel sided space thus formed between the front and middle banks, is disposed a superheater here shown as a plurality of U-tubes 25, connected to inlet and outlet headers 26 and 27 respectively, and substantially uniformly disposed across the space and filling the space. Extending upwardly from the lower water drum and 10 along the rear of the bank 5 is a baffle 28 connected by a cross baffle 29 to a baffle 30 on the front of the middle bank. This arrangement provides a tapering gas pass through which gases flow, contacting successively with the bank 5, the superheater and the middle bank 6. The gases then flow into the second pass which includes the tubes of the middle bank and which is defined between the baffle 30 and a second baffle 31, and then pass upwardly over the rear bank 20 and out the flue.

It has been found that the arrangements described above produce improved results in several respects. Priming is lessened, for one thing. The water level in the outlet or rear upper drum 25 is maintained sufficiently low to greatly reduce priming and the water separated from the steam in the front and middle drums may return to the bottom drum through tubes in a cooler pass directly without the necessity for passing to the next rearward upper drum. The superheater arranged between parallel banks of tubes, and filling the space and avoiding gas short circuits, makes possible a more compact efficient structure than where the banks of tubes are disposed at angles to each other, or where the space between banks is not filled, as is the usual practice. This arrangement, particularly in combination with the tapered gas pass over the superheater and opposite banks of tubes, results 30 in a boiler which is of high capacity, high efficiency, and with least variation of superheat as the load changes.

While there has been shown a certain selected embodiment of the invention, it is to be understood that the invention is not limited to this embodiment, but only by the scope of the appended claims.

We claim:—

1. In a Stirling type boiler, the combination of a rear steam off-take drum, a middle drum, a front drum, a lower drum, a baffle separating a high temperature gas pass from a low temperature gas pass, a first group of tubes in the latter

55

- gas pass directly connecting the lower and off-take drums and constituting the only direct connections between said drums, a second group of tubes in the low temperature gas pass directly connecting the lower and middle drums, a third group of tubes in the high temperature gas pass directly connecting the lower and middle drums, a furnace, a second baffle for the third group of tubes, a divided bank of tubes above the furnace and partly in front of the second baffle so as to be exposed to the radiant heat from the furnace gases, a superheater located between the divisions of the said last mentioned bank of tubes, and steam circulators directly connecting the middle and off-take drums, said first and second groups of tubes constituting the only connections between the water spaces of the middle and off-take drums, said combination acting to decrease the water level in offtake drum with increase in capacity at which boiler is operated.
2. In a water tube steam boiler, a boiler setting, a middle steam and water drum located between two similar drums at the top of the setting, a water chamber below said drums, tubes leading from said drums to the water chamber, baffles dividing the tubes into a plurality of separated banks located in separate gas passes extending through the setting, a lower number of the tubes in a bank leading to a drum from which a greater number of tubes extend downwardly through an adjacent gas pass of higher temperature, the tubes in each bank being bent at their upper ends so as to constitute diverging groups of tubes, secondary baffles between adjacent upper drums and having diverging portions extending along diverging tubes of said diverging groups of tubes, said secondary baffles forming gas pass walls guiding the furnace gases at their turns, a steam off-take connection communicating with the steam space of the rear upper drum, the middle upper drum having no water circulators directly connecting it with the rear upper drum, and steam circulators connecting the steam spaces of the rear and front upper drums to the steam space of the middle drum, water circulator tubes directly connecting the front and middle upper drums, a furnace, and a steam superheater located in the first gas pass from the furnace, the only water circulator connections between the middle and rear upper drums being through said groups of tubes which provide recirculation in the upper drums.
3. In a bent tube steam boiler including two natural circulation systems, a common boiler furnace, a separate steam and water drum for each system, a mud drum common to both systems, steam generating tubes for each system connecting the mud drum directly with the steam and water drum, downcomer tubes connecting each steam and water drum to the mud drum and exposed to furnace gases at temperatures lower than those of the gases contacting with the generating tubes leading to the same steam and water drum, an offtake steam and water drum having at increased ratings an effective steam space greater than the steam space of either of the other steam and water drums, steam circulators directly connecting the offtake drum and one of the first mentioned steam and water drums and constituting the only direct connection between them, other steam circulators directly connecting the steam and water drums, downcomer tubes directly connecting the offtake drum with the mud drum, an offtake drum feed water connection discharging feed water into the offtake drum, a superheater between the downcomer tubes and the steam generating tubes connected to the front drum of said steam and water drums, a rear baffle starting at the mud drum and extending upwardly along the rear tubes of the steam generating tubes leading from the mud drum to the front steam and water drum and terminating short of the front steam and water drum, and a baffle terminating short of the mud drum and located rearwardly of the superheater.
4. In a Stirling type boiler, the combination of a rear steam off-take drum, a middle drum, a front drum, a lower drum, a baffle separating a rear gas pass from a middle gas pass, a first group of tubes in the rear gas pass directly connecting the lower and off-take drums and constituting the only direct connections between said drums, a second group of tubes in the rear gas pass directly connecting the lower and middle drums, a third group of tubes in the middle gas pass directly connecting the lower and middle drums, a furnace, a second baffle in front of the third group of tubes, a divided bank of tubes above the furnace and partly in front of the second baffle so as to be exposed to the radiant heat from the furnace gases, the divided bank of tubes directly connecting the front and lower drums, a superheater located between the divisions of the said last mentioned bank of tubes, and steam circulators connecting the steam spaces of the middle and front and offtake steam and water drums said combination acting to increase the separation space of the off-take drum in proportion to the increase in capacity at which the boiler is operated.
5. In a Stirling type boiler, the combination of a rear steam off-take drum, a middle drum, a front drum, a lower drum, a baffle separating a middle gas pass of high temperature from a rear gas pass of low temperature, a first group of tubes in the rear gas pass directly connecting the lower and off-take drums and constituting the only direct connections between said drums, a second group of tubes in the rear gas pass directly connecting the lower and middle drums, a third group of tubes in the middle gas pass directly connecting the lower and middle drums, a furnace, a second baffle in front of the third group of tubes, a divided bank of tubes above the furnace and partly in front of the second baffle so as to be exposed to the radiant heat from the furnace gases, the divided bank of tubes directly connecting the front and lower drums, a superheater located between the divisions of the said last mentioned bank of tubes, and steam circulators connecting the steam spaces of the middle and front and offtake drums, said combination acting to increase the separation space of the off-take drum in proportion to the increase in capacity at which the boiler is operated.
6. In combination, a bent tube boiler having a mud drum, upper steam and water drums and banks of tubes connecting said drums including a front bank the tubes of which connect the mud drum and the front steam and water drum, and a second bank certain of the tubes of which connect the mud drum and a second steam and water drum and other tubes of which connect the mud drum and the front steam and water drum, said banks of tubes being so bent as to provide a substantial space therebetween for the major part of the longitudinal extent of the banks of tubes, a steam heater in said space, a rear baffle for the front bank beginning at the mud drum and

terminating short of the front steam and water drum, and a front baffle for the second bank terminating short of the mud drum and extending substantially parallel to the second bank.

5 7. In a water tube steam boiler of the Stirling type three upper drums including a front and rear drum, a lower drum, a front bank of inclined steam generating tubes directly connecting the front drum to the lower drum, a second bank of 10 tubes connecting the lower drum to the two forward upper drums and having their lower portions extending from the lower drum at a considerable angle away from the general direction 15 of the tubes of the front bank and their main portions spaced substantially rearwardly of the front bank of tubes and extending generally parallel thereto towards the upper drums, and a third bank of tubes communicating with the lower drum at positions rearwardly of the second bank 20 and having lower substantially straight portions extending substantially vertically from lower drum and forming with the lower portions of the second bank a substantially continuous tube bank, the remaining portions of the tubes of the third bank being bent substantially forwardly from 25 their lower portions and extending upwardly towards the upper drums.

8. In a water tube boiler of the bent tube type, a furnace, a first main natural circulation system including an upper drum and a lower drum directly connected by tubes in two separated and spaced groups exposed to heating gases at different temperatures, one group constituting steam generators exposed directly to heat from the furnace, a second main natural circulation system distinct from the first and including a separate upper drum directly connected to the above mentioned lower drum by tubes separated into two groups one of which is exposed to heating gases in the same gas pass as one of the groups of the first mentioned tubes, baffle interposed relative to the two groups of tubes in the second system, a third upper drum, a steam off-take connection above and leading from the third drum, a bank of tubes directly connecting the third drum to the lower drum and exposed to heating gases after they have contacted with the tubes of the other groups, steam circulators connecting the steam spaces of the upper drums and a superheater positioned forwardly of the baffle and rearwardly of tubes of one of said first mentioned groups of tubes, the steam and water separation for the boiler taking place in two main stages with a primary stage independently taking place in the drum for each circulation system and a secondary separation common to both systems and taking place in the third drum.

9. A water tube boiler including a lower drum, three upper steam and water drums including a rear drum, a furnace, baffles dividing the gas space

below the upper drums into gas passes of different temperatures, a bank of tubes directly connecting the lower drum with the front steam and water drum and disposed in the gas pass nearest the furnace and of highest temperature, tubes directly connecting the lower drum with the front drum and disposed in a second gas pass of lower temperature than the first, tubes in a third gas pass directly connecting the rear drum and the lower drum, separated groups of tubes connected to the middle upper drum and the lower drum and subjected to heat from the furnace gases at separated positions of materially different temperatures, circulators directly connecting the steam spaces of the upper drums, and a superheater positioned rearwardly of tubes of the first mentioned bank of tubes and forwardly of said baffles, the steam and water separation for the boiler taking place in two main stages with a primary stage taking place in each of the middle and front upper drums 20 and a secondary separation common to both independent primary separations taking place in the rear drum.

10. In a water tube steam boiler of the bent tube type, three consecutively arranged upper steam and water drums including a rear steam off-take drum, a lower water chamber, a furnace from which heating gases pass between the drums, baffles dividing the gas space into three gas passes separately extending from the water chamber 30 toward the upper drums, three separate banks of tubes with each bank constituting substantially parallel tubes extending through one of said gas passes and substantially directly from said chamber to an upper drum, said separate banks 35 diverging from the chamber to materially spaced positions beneath the upper drums to which they are respectively connected, cross-over tubes arranged in a bank and extending from the foremost steam and water drum directly toward a position immediately beneath the middle steam and water drum and thence alongside the tubes of the middle bank, some of the cross-over tubes extending thence through the second gas pass in positions generally parallel to the tubes of the middle bank to the water chamber while the remainder similarly extend through the first gas pass immediately in front of the first baffle, a steam-offtake connection leading from the rear upper drum, steam circulators directly connecting the steam spaces of the offtake and middle upper drums, other steam circulators directly connecting the middle and front upper drums, said remainder of the cross-over tubes being disposed at a substantial distance rearwardly of the front bank of tubes, and a drainable superheater disposed between said remainder and the front bank.

HOWARD J. KERR.
